CLAIM

The ornamental design for a retractor for coronary artery bypass surgery, as shown and described.

DESCRIPTION

FIG. 1 is a perspective view of a retractor for coronary artery bypass surgery showing our new design; the broken line showing of the chest cavity is for illustrative purposes only and forms no part of the claimed design;

FIG. 2 is a top view thereof;

FIG. 3 is a bottom view thereof;

FIG. 4 is a front view thereof;

FIG. 5 is a rear view thereof;

FIG. 6 is a right side view thereof; and,

FIG. 7 is a left side view thereof.
